ROLFE R. HOLBROOK, OF DETROIT, MICHIGAN, ASSIGNOR OF TWO-THIRDS TO HARRY E. MARSHALL, OF HIGHLAND PARK, MICHIGAN.

DEVICE FOR PREVENTING REUSING OF BOTTLES.

1,151,102.

Specification of Letters Patent. Patented Aug. 24, 1915.

Application filed May 8, 1915. Serial No. 26,701.

To all whom it may concern:

Be it known that I, ROLFE R. HOLBROOK, a citizen of the United States, residing at Detroit, county of Wayne, State of Michigan, have invented a certain new and useful Improvement in Devices for Preventing Reusing of Bottles, and declare the following to be a full, clear, and exact description of the same, such as will enable others skilled 10 in the art to which it pertains to make and use the same, reference being had to the accompanying drawings, which form a part of this specification.

This invention relates to a device for preventing the re-using of bottles after the contents have once been emptied.

In the drawings,—Figure 1 is a vertical section of a bottle neck and the non-re-use device. Fig. 2 is a vertical section of the 20 bottle neck and the non-re-use device, showing how the parts operate when the bottle is canted. Fig. 3 is an elevation of the shell of the device. Fig. 4 is a perspective of the cork gasket. Fig. 5 is a detail of one of 25 the clips that hold the non-re-use device in place. Fig. 6 is a bottom view of the non-re-use device showing how one arm and one recess are offset from the true quarter point.

The shell *a* is preferably made of porcelain 30 although it may be made of blocked tin or such other suitable material as will not taint the liquid. The top of the shell is provided with an annular flange *b* to prevent its being dropped or forced down below 35 the internal rib *c* in the neck of the bottle. The shell *a* is provided with a plurality of longitudinal slots *d* that extend upwardly from the bottom about half the height of the shell. One of these slots (see Fig. 6) is 40 offset from what would be the quarter point, where four slots are used. Similarly, the spindle *e* of the plug or valve is provided with a plurality of radially extending arms *f*, one of which is offset from the quarter 45 point as shown in Fig. 6. The consequence of this arrangement is that the arms will only enter the slots when the arms are at one certain position in the whole 360 degrees in which they may be turned. If the 50 four arms were all equally spaced as also the slots, it is apparent that there would be four positions in the 360 in which the arms could enter the slots. This arrangement has a distinct relation to the possibility of again lifting the spindle in the

guide slots of the bottle, as will be herein-after explained.

The spindle *e* is preferably made of porcelain or blocked tin to prevent tainting of liquids. Its upper end enlarges into an inverted cone on the top of which is located a calf-skin washer *g*. I have, by the way, found that a calf-skin is one of the very few suitable washers for this purpose, as unlike rubber and similar substances, it will not 60 taint the liquids nor will it dry or crack, while at the same time it affords a very suitable gasket and holds the cork *h* normally in the position shown in Fig. 1, that is, loosely resting on the top of the shell *a*. 70 The top of the spindle *e* ends in a pointed stem *i* upon which can be impaled the cork *h*. The cap *j* having a perforation at its top, is adapted to fit over the cork and be crimped under the flange *b* of the shell *a*. 75 It may be made of pressed paper, blocked tin or some similar material which will not affect the contents of the bottle. A gasket of cork *k* in the form of a ring, slips over the lower end of the shell and fits under the 80 annular flange of the shell. Hence when the device is seated in the neck of the bottle this cork engages with the rib, as shown in Figs. 1 and 2, to make the connection liquid-tight.

A couple of spring clips *l*, as shown in 85 Fig. 5, each provided with a projecting shoulder portion and an inturned upper portion can be used to lock the device from being withdrawn from the neck of the bottle. The inturned upper portion engages in a 90 recess in the cork and shell. It will readily be understood that when the device is forced down into the bottle the inclined lower ends of the clips allow them to pass the internal rib *c* of the bottle neck, but that as soon as the shoulders of the clips have passed the lower side of the rib, they will immediately snap thereunder and prevent its ever being withdrawn under ordinary circumstances. These clips are heavily block-tinned or 95 nickel-plated.

The operation of this device is as follows: The distiller or other manufacturer first fills the bottle, then the non-re-use device is inserted in the neck of the bottle by forcing 105 it inwardly therein until the shoulders of the clips *l* snap under the annular rib *c*. The device is now in place and cannot be withdrawn under ordinary circumstances. When the bottle is canted, as shown in Fig. 110

2, the contents will flow out under the ordinary check valve principle. When it is attempted to re-fill the bottle, standing in the position shown in Fig. 1, it will readily be seen that the cork will rest upon the top orifice of the shell by reason of being supported by the washer *g*. In this position the washer *g* will sufficiently seal the orifice of the shell so that no substantial amount of liquid can be introduced this way. It might be possible to force liquid around the plug by means of pressure, but as soon as pressure is applied to the cork, the plug will be forced into the shell and the arms *f* of the plug will drop out of the slots and below the bottom of the shell. They will in almost every case immediately get out of registry with the set of slots, and it is only by a rare chance that they can again be brought to register with the slots so the cork can be shaken out. Of course if it was possible to get a grip on the cork, it would not be a great deal of trouble to turn the plug around until finally the one point in the 360 where the arms register with the slots was secured. However, by merely shaking—and that is the only way open to endeavor to make the arms register with the slots—there is only a remote possibility of getting the plug to jar out again. Hence with the plug drawn into the shell and the washer *g* pressed tightly against the wall of the orifice of the shell, little or none of the contents will come out when the bottle is canted, for the only pressure urging the contents out is their weight, and there will be scarcely any place for air to get in to get atmospheric pressure behind the contents. Hence nothing more than a few drops will come out notwithstanding unusual efforts by shaking. If any one attempts to lift the cork by sticking a hat-pin thereinto, after the arms have dropped below the bottom of the shell and gotten out of registry with the slots, the cork will pull off from the top of the spindle *i* before the plug can be put into place by endeavoring to exercise force enough to break off the arms.

What I claim is:

50 1. A device of the class described, having in combination, a shell, means for securing the same in a bottle neck, a cap engaging with the top of the shell, the said shell being provided with a plurality of slots extending longitudinally upward from the bottom of the shell, the said slots being arranged so that some of the slots are unequally distant from each other, and a plug

engaging in the cap and shell and provided with radially extending arms guided in the 60 said slots, the said arms being arranged to correspond with the unequal spacing of the slots, substantially as described.

2. In a device of the class described, the combination of a shell having longitudinal slots extending upwardly from the bottom and a flange on the upper end of the shell, a cap fitting under the flange of the shell, some of the slots of the said shell being arranged so as to be unequally spaced 65 from each other, and a plug engaging in the shell and cap and provided at its lower end with radial arms some of which are unequally spaced to correspond with the spacing of the slots in the shell, substantially as 75 described.

3. A device of the class specified, having in combination, a shell provided with longitudinal slots extending inwardly from the bottom thereof, a cap engaging with the top 80 of the shell, some of the said slots in the shell being unequally spaced, a plug engaging in the shell and cap and comprising a spindle portion having in its lower end radial arms some of which are unequally 85 spaced to correspond with the spacing of the slots in the shell, the said spindle enlarging toward its upper end, a flexible washer on the top of such enlargement, and a cork 90 fitted upon the top of the washer and secured to the said spindle.

4. In a device of the class specified, the combination of a shell provided with slots extending longitudinally inward from the bottom thereof, a cap interlocked with the top of the shell, a plug engaging in the shell and cap and comprising a spindle having radial arms engaging with the slots of the shell, the said spindle enlarging toward the top and forming a shoulder between the enlargement and a stem extension, a flexible washer fitting over this shoulder for engaging the top of the shell, and a cork impaled upon said stem and fitting against the said washer, the said slots and arms of the shell and plug respectively being arranged so that there is unequal spacing between some of the individual members of each set so that the slots and arms can register at only one point in the 360 degrees.

In testimony whereof, I sign this specification in the presence of a witness.

ROLFE R. HOLBROOK.
